UNITED STATES PATENT OFFICE

132,142

DESIGN FOR A SURGICAL KNIFE

Ernesto A. Balla, New Bedford, Mass.

Application December 19, 1941, Serial No. 104,746

Term of patent 14 years

To all whom it may concern:

Be it known that I, Ernesto A. Balla, a citizen of the United States, residing at New Bedford, in the county of Bristol and State of Massachusetts, have invented a new, original, and ornamental Design for a Surgical Knife, of which the following is a specification, reference being had to the accompanying drawing, forming part thereof.

Figure 1 is a side elevational view of a surgical knife embodying my new design.

Figure 2 is a view in top plan.

Figure 3 is a view in elevation at the left end of Figure 1, and

Figure 4 is an elevational view at the right end of Figure 1.

The characteristic features of the design for the surgical knife disclosed reside in the cutting end portions having the configuration shown.

I claim:

The ornamental design for a surgical knife, substantially as shown and described.

ERNESTO A. BALLA.
